(57) **CLAIM**

The ornamental design for a shoe midsole, as shown and described.

DESCRIPTION

FIG. 1 is a medial side perspective view of the new design for a shoe midsole;

FIG. 2 is a lateral side perspective view thereof;

FIG. 3 is a lateral side view thereof;

FIG. 4 is a medial side view thereof; and,

FIG. 5 is a rear view thereof.

The dash-dot broken lines in the drawings define the bounds of the claimed design and form no part of the claimed design.

The dash-dash broken lines showing the remainder of the shoe are for environmental purposes only and form no part of the claimed design.

A left-foot shoe is illustrated in FIGS. 1-5. A second embodiment of the design includes a right-foot shoe, which is a mirror image of the embodiment illustrated in FIGS. 1-5.
